UNITED STATES PATENT OFFICE.

HOWARD DELANO, OF SYRACUSE, NEW YORK.

FEEDING FUEL TO FURNACES.

Specification of Letters Patent No. 12,546, dated March 20, 1855.

To all whom it may concern:

Be it known that I, HOWARD DELANO, of Syracuse, in the county of Onondaga and State of New York, have invented a certain 5 new and useful Improvement in the Manner of Feeding in Fuel to Furnaces and Fire-Boxes of All Kinds; and I do hereby declare the following to be a full, clear, and exact description of the same, reference being had to the accompanying drawings, making a part thereof, in which—

Figure 1, represents a vertical section through a fire box, and showing the apparatus by which the fuel is fed into it. Fig. 15 2, represents a view looking up from the under side of Fig. 1—or of Fig. 1 turned upside down. Fig. 3, represents, the feed box and grate or cut-off, detached, and Figs. 4, 5, 6, and 7, represent views of the several 20 pieces for operating the feed box and grate or cut off, detached, and uncombined with each other.

Similar letters in the several figures denote like parts.

25 A, represents the top plate of a stove or furnace, in the center of which is placed a fire box B, the bottom of which is open, and the sides furnished with openings a, a, a, to admit air to the burning fuel. The fire box 30 is bowl-shaped, or flaring from its bottom upward, the object being to furnish the fresh fuel in the center of the burning mass, for two purposes—first to cause the gases from the fresh coal to pass through the burning 35 mass above it, and thus consume it, and secondly to protect the sides of the fire box from the intensity of the fire, by keeping the lesser heat of the mass in contact with said sides which admits of the fire box being 40 made of thin metal.

C, C, are two ways underneath the top plate A, in which the feed box D, and grate or cut off slides, as will be described.

E, is a bracket or bail, extending downward from opposite sides of a ring b (as seen in Fig. 7) and in the lower ends of which bracket or bail, is a wrist pin c, to which one arm of a divided or forked lever F, is connected, the fulcrum of said lever being at d.

G (Fig. 4,) is a slotted piece of metal firmly united to the feed box D, and having a projection e upon it, which receives the ring b, when it comes to the bottom of the 55 feed box, and prevents it from dropping too low. The lever F, is fastened or pivoted

to the piece G, at d. On the side of the piece G, is pivoted at f, a trigger H, in the edge of which a slot g, is cut, to receive a pin h, in the lever F, this being for the purpose of holding up, and then tripping the ring c, as will be described in the operation of feeding in the fuel.

I, is a crank shaft, supported in the suspended arms J, and having a crank K upon it for rocking or turning it. The crank part of this shaft I, works in the slot L, of the piece G, and gives to said piece G, and the several parts connected with it, a reciprocating motion, each way of the center of motion of the crank shaft. This motion will be variable, for as the crank part of the shaft is moving vertical either in going up or coming down, it will but slightly move the part G, if at all. But when at the upper or lower part of its arc, it will move G, and its accompanying parts over a space equal to twice the length of the crank.

I have spoken of one arm of the lever F, and its functions. There is also another 80 though shorter arm M, which projects across the slot L, and as the crank shaft rises through said slot, it catches underneath said arm M, and raises it, together with the lever F, of which it is a part, upward until the 85 pin h takes into the slot g. In raising up F, of course the ring b, in the feed box which is connected to it rises also, and just before the crank part of the shaft I, slips past the arm M, the pin h, has entered the slot g, in 90 the trigger H, which continues to hold up the lever F, after the crank shaft I, has passed the arm M. By this means the ring b, and its cover i which forms a tight bottom (though a removable one) in the feed 95 box D, is held up until it is first, by the continued operation of the crank moved in its ways, C, and the descent of the crank part, forces the trigger H, away from the pin h, which allows it to drop until it reaches e, 100 where it is held. Before the crank shaft trips the trigger H, it (the shaft) has passed below the arm M, which leaves said arm in proper position for the next operation.

D, represents the feed box and D' the 105 grate bars or cut off. These two are connected together, so that as they are slid to and fro underneath the fire box B, one or the other shall hold up the fire in said box. D', are not necessarily grate bars, though I prefer them as such, for by a simple working 110 of the crank K, the fire can be raked down,

or agitated; its particular duty is to retain the coal in the box, as draft can be introduced elsewhere, if not sufficient through the openings *a*, and acts as a cut off, to prevent the coal from falling out of the fire box.

The advantages arising from the feeding in of the coal underneath the mass, is that the gases arising therefrom pass through the burning mass on top of it, and are consumed, 10 which saves fuel, whilst the gas pipe which is ordinarily several inches in diameter for leading off the gases, need not in my case be over two inches in diameter for stoves. I also save the burning out of the fire box 15 by keeping the dense heat and burning gas, in the center of the fire, keeping the surrounding though less heated products as a shield to the metal.

The operation of feeding in the coal is as 20 follows. The feed box is run out to the opening in the top plate A (Fig. 2,) and the coal thrown into said box, the bottom being down as seen in Fig. 1. The crank is now 25 turned which first draws the feed box immediately underneath the fire box, and by continuing the turning the bottom of the feed box, and the coal on it, is forced up into the fire box, underneath the burning fuel therein. By continuing to still further turn 30 the crank, the feed box is run back, while the grate bars, or cut off takes its place, and hold the coal in the fire box. Kindling may

be introduced in the same way to the fire. By removing the lid or cover *i* from the ring, and running the feed box empty underneath the fire box—its whole contents will drop through said feed box, into the ash pit below.

I design applying this mode of feeding in fuel to furnaces, locomotives, heaters, and 40 stoves of all kinds, and the mechanical means will of course vary with the particular fire box, or chamber to be fed, or its locality. But these changes would be obvious, and fairly come within the scope of my invention.

Having thus fully described the nature of my invention, what I claim therein as new and desire to secure by Letters Patent is—

1. The combined use of the feed box and 50 grate bars or cut off, for feeding in fuel into the under part of the burning mass in the fire box or their mechanical equivalents, as described.

2. I also claim the combination of the 55 crank shaft I, slotted piece G, lever F, and trigger H, or their mechanical equivalents for sliding the feed box and grate or cut off, and for raising and lowering the bottom of the feed box, substantially as described. 60

HOWARD DELANO.
